UNITED STATES PATENT OFFICE.

FREDERICK NELSON, OF ST. PAUL, MINNESOTA.

BLIND-SLAT OPERATOR.

SPECIFICATION forming part of Letters Patent No. 284,222, dated September 4, 1883.

Application filed March 5, 1883. (Model.)

To all whom it may concern:

Be it known that I, FREDERICK NELSON, a subject of the King of Sweden and Norway, having declared my intention of becoming a citizen of the United States, and residing at St. Paul, in the county of Ramsey, in the State of Minnesota, have invented certain new and useful Improvements in Blind-Slat Operators, of which the following specification is a full, clear, and exact description, reference being also had to the accompanying drawings.

This invention relates to window-blinds having pivoted slats; and it consists in the method of opening, closing, and locking the slats in any desired position, as hereinafter described and shown, and then sought to be specifically defined by the claims.

In the drawings, Figure 1 is a front view, Fig. 2 is a cross-sectional view, and Fig. 3 is a semi-sectional side view, of one section of a window-blind, showing my improvements attached thereto. Figs. 4 and 5 are enlarged detached detail perspective views of portions of the working parts. Fig. 6 is an enlarged sectional front view, Fig. 7 is an enlarged sectional side view, and Fig. 8 is a cross-sectional view, of the lower portions of the blind-slat-operating rods and their locks. Fig. 9 is an enlarged front view similar to Fig. 6, showing the additional attachment to enable outside blinds to be operated from inside the house without raising the sash. Fig. 10 is an enlarged perspective view of the lower end of the key which is used to operate the additional attachment shown in Fig. 9. Fig. 11 is an enlarged detached perspective view of the pinion and its slotted head. Figs. 12, 13, and 14 are views illustrating a slight variation in the means for operating the slat-moving rods. Figs. 15 and 16 illustrate the manner of forming and protecting the key-hole through the window sash or glass when the additional feature shown in Fig. 9 is used.

A is the frame; B, the slats, and a' a² the bars connecting the slats to each other, arranged as in an ordinary window-blind.

Lying upon one of the jambs of the blind is a rod, b', preferably of flat metal, and adapted to be moved up and down a short distance through guides or caps c' c², which hold it in place loosely upon the jamb.

Attached to the rod b' near its upper end, just below the upper guiding-cap, c', is an arm, d', projecting outward and off toward the upper section of slats B, as shown, and adapted to be clasped by the forked end e' of an arm, C', and pivoted in said forked end by a rivet or pin, so that the arm C' will be free to oscillate laterally upon the arm d', but prevented from moving perpendicularly by reason of the arm d' being held in the fork e', as shown. The opposite end of the arm C' is provided with oppositely-branching feet g', by which it is connected to the slat-moving bar a' rigidly, and both ends move up and down simultaneously therewith. By this means the moving of the rod b' up and down will cause the arm C' to open and close the slats B of the upper section of the blind, the lateral play of the fork e' on the arm d' permitting the slats to open and close without cramping the parts.

b' is a short flat metal rod, similar to the rod b', lying partially upon top of the lower part of the rod b' and partially alongside of it, as shown, and provided with an arm, d², similar to the arm d' on the rod b', and fitting into a fork, e², on an arm, C², having feet g², by which it is rigidly connected to the bar a² of the lower section of the slats B in precisely the same manner as the arm C' is attached to the bar a' of the upper section of slats. The upper end of the rod b² runs beneath a grooved cap, h, (see Fig. 5,) the rod b² having a rib, i, adapted to fit into the groove of the cap, while the lower ends of both the rods b' b² pass beneath a "housing" or guide-cap, E. Each of the rods b' b² is provided with teeth m' of the same size and form, into which a small lug, n, on the inside of the housing E is adapted to fit, as shown in Fig. 6. Each of the rods b' b² is provided inside the housing E with a small independent spring, r' r², by which the teeth m' of the rods are held in contact with the lug n. These springs may be arranged and applied in any desired manner; but for the purpose of illustration I have shown them of different forms and lengths, so that the edge of one will always overlap the edge of the other in whatever position they may be, so that one spring cannot get upon top of the other, but each will retain the same relative position upon its own rod b' b². The rod b' will be longer than the rod b² and

project down below it, as shown, and each rod will be provided with a separate knob, $F' F^2$, by which the rods may be moved up and down more easily and independent of each other.

5 By forcing either one of the knobs $F' F^2$ inward toward the slats B until the teeth m' are free from the lug n , either one of the rods b' or b^2 may be moved up or down to open or close the slats B to any desired extent, and then 10 when the knobs are released the springs r' or r^2 will throw the rods b' or b^2 outward again and cause the lug n to enter whichever one of the teeth m' is opposite to it. By this means the slats B may closed entirely or opened to 15 any desired extent and locked by the lug n and teeth m' in any desired position. By this means the slats may be opened entirely and locked open, or closed entirely and locked shut, or opened to any extent and locked in that position. I can thus regulate the amount of light admitted, prevent rattling or moving by the wind, and in outside blinds prevent the slats being turned by persons from the outside.

The parts will be reversed for right and left 25 hand blinds, and will be formed to project as little as possible from the face of the blind, so as not to interfere with the window-sash.

The two rods $b' b^2$ may be arranged entirely 30 independent of each other at the bottom, if desired; but by arranging them as shown one cap, E, and lug n can be made to do duty for both, and the parts made to occupy less room on the blind.

The arms $C' C^2$ may be forked, as shown by 35 dotted lines C^3 in Fig. 1, to add strength to the arm.

This device may be used on either inside or 40 outside blinds, the parts simply requiring slight changes of proportions and positions to adapt them to different kinds and sizes of blinds.

The extensions on the small arms $d' d^2$, which 45 project into the forks $e' e^2$ of the arms $C' C^2$, may be dispensed with in some cases without detracting from the perfect operation of my 50 invention, the additional length of these arms $d' d^2$ giving greater stiffness to the connection between the arms $C' C^2$ and $d' d^2$.

When used as shown in Fig. 1 on outside 55 blinds, the lower sash will have to be raised a short distance to enable the knobs $F' F^2$ to be reached, and to enable the slats to be operated from the inside of the window and without raising the sash.

I form gear-teeth m^2 upon the same side of 60 the rods $b' b^2$ as the teeth m' , and below them, as shown in Fig. 9, and mount a pinion, t' , in a hanger, t^2 , and arranged to mesh into the teeth m^2 . The width of the faces of the teeth of the 65 pinion is the same as the faces of the teeth m^2 , and the space below the hanger t^2 is large enough to permit the pinion to be pulled outward to engage with the teeth m^2 on the rod b^2 , or be pushed inward to engage with the teeth m^2 on the rod b' , so that each rod may be operated separately. The hole in the hanger t^2 ,

through which the shaft t^2 of the pinion t' passes, is slotted, so that the pinion may be moved to one side to force the rods $b' b^2$ inward and disconnect the teeth m' from the lug n 70 when the pinion is to be used, the pinion thus acting in the same manner as the knobs $F' F^2$, as far as unlocking the rods is concerned. A peculiar-shaped head is formed upon the shaft of the pinion t' , outside the hanger t^2 , consisting of a T-slot, t^4 , formed crosswise through the head, and with the shank part t^5 of the T-slot opening out through the face of the head. t^6 is another small slot opening out through the end of the head, so that a T-head on a key, 80 G, (see Fig. 10,) may be set into the slots t^4 and t^5 , and then pushed in to force the pinion t' inward and be turned by the key to move the rod b' , or pulled outward and turned by the same key to move the rod b^2 . By this 85 means the pinion may be made to act upon either set of the teeth m^2 on the rods $b' b^2$. A hole will be made in the lower part of the sash, through which the key G may be inserted to operate the pinion, and the hole adapted to 90 be covered to keep out the cold when not in use. In some cases it will be necessary to form this key-hole for the key G through the glass itself. In this event I will use the device illustrated in Figs. 15 and 16, consisting in cutting a hole, v' , in the glass somewhat larger in diameter than the width across the T-head of the key G. A strip of soft rubber, v^2 , is then folded over the edge of the glass to completely 95 cover the hole v' on both sides of the glass, and secured in that position on the glass in any suitable manner, either by a rivet, v^3 , as shown, or in any other manner. Small holes the same size as the shank of the key G will be formed 100 through the rubber piece v^2 , opposite the centers of the hole v' in the glass. By this means the soft rubber will stretch and permit the larger head of the key to be passed through the hole v' and then close around the shank of the key and prevent cold air from entering. 105

A hard rubber or metal flap or cover v^4 will be arranged to cover the key-hole when not in use, and may be provided with a spring, v^5 , to cause it to be self-closing, and remain closed when not pushed one side to insert the key. 115 When the key-hole is formed through the sash, only one single piece of the soft rubber v^2 and the flap v^4 will be used on one side of the sash.

When the additional feature shown in Fig. 9 is used on blinds with narrow jambs, the housing E and springs $r' r^2$ will be reversed and the teeth $m' m^2$ formed on the inner edges of the rods $b' b^2$, but the action will be the same.

Figs. 12, 13, and 14 represent a slight variation in the mechanism for moving the rods $b' b^2$, consisting in forming the teeth m' in the form of gear-teeth and adapting the rods to be moved up and down by a pinion and key constructed and arranged in the same manner as the pinion and key shown in Figs. 10 and 11. 125

Having described my invention and set forth its merits, what I claim is— 130

1. In a blind-slat fastener, the combination, with the pivoted slats B B and their connecting-bars $a' a^2$, of actuating-rods $b' b^2$, sliding in guide-caps on the blind-frame, and provided 5 with locking-teeth $m' m'$, connecting-arms $C' C^2$, rigidly attached to the slat-bars $a' a^2$, and pivoted laterally to the actuating-rods, the locking lug or stop n , and springs $r' r^2$, substantially as and for the purpose herein specified.
- 10 2. The combination of the sliding actuating-rods $b' b^2$, provided with locking-teeth $m' m'$, the stop n , springs $r' r^2$, and the pinion t' , having a lateral movement in its bearings, whereby it is adapted to unlock the said actuating-
- rods and to move them up and down, substantially as herein specified. 15
3. The pinion t' , having an axial movement in its bearings, and provided on its shaft with a head having a T-shaped slot adapted to receive a key, for both pushing and pulling and 20 for turning the pinion, substantially as and for the purpose specified.

In testimony whereof I have hereunto set my hand in presence of two subscribing witnesses.

FREDERICK NELSON.
